DESIGN FOR A HYDROMETER SYRINGE

Carl J. Dunzweiler, Cleveland, Ohio, assignor to
Willard Storage Battery Company, Cleveland,
Ohio, a corporation of West Virginia

Application June 6, 1938, Serial No. 77,641

Term of patent 14 years

To all whom it may concern:

Be it known that I, Carl J. Dunzweiler, a citizen of the United States and a resident of Cleveland, in the county of Cuyahoga and State of Ohio, have invented a new, original, and ornamental Design for a Hydrometer Syringe, of which the following is a specification, reference being had to the accompanying drawing, forming a part thereof, in which

Fig. 1 is a side elevation of the hydrometer syringe embodying my new design; and

Fig. 2 is a top plan view thereof.

I claim:

The ornamental design for a hydrometer syringe, substantially as shown.

CARL J. DUNZWEILER.
